UNITED STATES PATENT OFFICE.

ROBERT PEEL BEALE WILSON, OF HUTCHINSON, KANSAS.

INSIDE DOOR FOR RAILWAY CARS AND THE LIKE.

Application filed July 8, 1922. Serial No. 573,542.

To all whom it may concern:

Be it known that I, ROBERT PEEL BEALE WILSON, a citizen of the United States, residing at Hutchinson, in the county of Reno, State of Kansas, have invented a new and useful Inside Door for Railway Cars and the like, of which the following is a specification.

My invention relates to an improved ¹⁰ side door for box cars used in carrying grain and other commodities, and the object of my invention is,

First, to provide a practical door which may be used in said box cars over and over ¹⁵ again when the box cars or other cars are loaded with grain and such freight.

Second, to provide a door which when not in use may be securely fastened to the inside of the box or other car and be practically ²⁰ out of the way.

Third, the provision of a small opening secured by a door, in the inside door which may be made any size or shape to suit, or may be left out altogether.

Fourth, to furnish a door of the character set forth which saves the expense and trouble of boarding up the doors of a box car when loaded with grain and such freight.

I attain these objects by the mechanism ³⁰ illustrated in the accompanying drawing, in which—

Figure 1 is an elevation of the inside door as it appears from the outside of the box car.

Figure 2 is a sectional view of the threaded tube or ferrule with flange at one end, the crank bolt being screwed into same, and through the inside door.

Figure 3 shows the inside door securely fastened as it appears from the inside of the ⁴⁰ box car.

Figure 4 is the front view of the crank bolt when fastened in place.

Figure 5 is the front view from the outside of the box car, showing the flange of the threaded tube or ferrule.

Figure 6 is a view of the top edge of the inside door, which may be bent at a right angle along the top, or an angle iron attached to add strength.

Figure 7 shows that the top of or the edge ⁵⁰ may be looped along same to add strength.

Figure 8 is the interior view of the inside door, when securely fastened to the side of the box car when out of use, the crank

bolts being in pendant position ready for ⁵⁵ use.

Similar numbers refer to the similar parts throughout the several views.

The inside door 3 is attached to the sides of the box car door 1, 1, by means of the ⁶⁰ crank bolts 5 which pass through the holes 18 in inside door 3 the bottom of the inside door

3 resting against the metal threshold 2, that is already found in the ordinary box car. The fasteners of the inside door 3 are com- ⁶⁵

posed of a plurality of threaded hollow tubes or ferrules 4 each being provided with a flange at one end, in which ferrules are screwed the crank bolts 5. The threaded tubes or ferrules 4 are inserted in the door ⁷⁰

posts 1, 1, of the box car in a series, which is shown in Figure 1 and as shown by sec- ⁷⁵

tional view more plainly in Figure 2, said ferrules being angular in cross-section so as to prevent turning. The box car is equipped ⁸⁰

with a sufficient number of the threaded tubes or ferrules 4 which have a flange 6 and a number or series sufficient according to the size of the box car and inside door need- ⁸⁵

ed. In these figures are a series of four, ⁹⁰ threaded flanged hollow tubes or ferrules 4 which can be increased or decreased as nec-
essary, that is a series on each side of box car door 1, 1, and one series to right of box car door with a corresponding number of ⁹⁵

holes 18 in the inside door 3. The inside door 3 is swung into place by means of two chains 15 which are attached to a rod or pipe ¹⁰⁰

13 which may be the track from which the wheeled outer door is suspended being fas- ¹⁰⁵

tened to or near the roof of the box car, by means of brackets 14. The chains 15 slide along the rod or hollow pipe 13, to which they may be placed, and serve to keep the ¹¹⁰

inside door 3, attached by links 17, 17, from falling down or being lost or misplaced from the box car. When the inside door 3 is placed across the box car door as shown by Figures 1 and 3, then it can be securely ¹¹⁵

fastened to the side posts 1, 1, of the box car by means of the crank bolts 5 and threaded tubes or ferrules 4. The crank bolts 5 are threaded at one end, while the other end is provided with a handle at right angles with ¹²⁰

the bolt, and when screwed into the threaded tubes or ferrules 4, after passing through the corresponding holes 18 will not unscrew ¹²⁵

themselves as the handles which are of suffi-

cient weight prevent them unscrewing, gravity holding them in place as shown in Figure 3. The threaded tubes or ferrules 4 are equipped with a flange so that they cannot be pulled through the posts 1, 1, in which they are inserted and are countersunk, so that they are flush with the outside of the box car posts 1, 1, as shown in Figure 1, they being held in place so that they will not shake out by means of two ordinary screws, 6, which latter also prevent turning of tubes or ferrules 4, see Figures 2 and 5. The crank bolts 5 screwed through inside door 3 at holes 18, have a flange 7, which turns against the inside door 3 and holds the inside door 3 securely against the ends of the threaded tubes or ferrules 4 which are placed in the box car door just flush with the inside of the box car door posts 1, 1. The crank bolt 5 is attached to the chain 16 which is a chain lighter than chain 15 so that they will not be lost or misplaced being always handy for use, and are attached to chain 16 by means of yoke links 19 between the flanges 7, 7. The yoke links 19 allow the crank bolts 5 to be turned and screwed into place without twisting the chain 16 which holds them as shown in Figures 3 and 8. The inside door B or 3 may be reinforced or strengthened by means of angle irons according to the size of the door. The top of the inside door 3 may be strengthened by turning the top at a right angle to the door as shown in Figure 6 or by using angle irons, or the upper edge of the door can be looped as shown in Figure 7. In the inside door 3 can be cut an opening of any shape or size, and as shown in Figures 1, 3, 8, which show a door way 9, cut in the shape of a rectangle, with a hinge 40 or bolt 11, which may be an ordinary bolt or rivet which holds it in place and allows the door 8 to be lifted or opened. The opposite end of the opening is a hook or clip 12, into which the extended or projected part of the door 8 drops or fastens, which holds same in place securely the door 8 being further secured by means of four or more stud bolts 10 which are screwed into the inside door 3. These stud bolts have to be unscrewed to allow the door 8 to be lifted or opened, and may be secured if desired by chains to the inside door that they will not be lost. By means of the hinge 11, fastenings 12 and the stud bolts 10, the door 8 will not become loosened or opened so as to let grain or other freight run out unless and until they are removed if it is desired to open same to unload the grain or other freight.

Figure 8 shows the inside door 3 swung back to the right in the box car where to remain out of the way when not in use, and on the left shows the inside door 3 secured to the door post 1 of the box car. On the right of the inside door 3 the crank

bolts 5, hanging by means of chain 16, are ready for use to be screwed into place through the door 3 and into series of threaded flanged tubes which would appear the same as shown on the left door post 1. The 70 threaded tubes or ferrules 4, at the right of the door of course are hidden by the inside door 3, chain 16 and swinging crank bolts 5, attached to said chain 16. The inside door 3 is shown to be attached to chain 75 15 by links 17, 17, also in the inside door are bored holes 18 at each end, so crank bolts 5, may pass through and be screwed into the threaded tubes or ferrules, 4, which secures inside door 3 to box car posts 1, 1, so as to hold grain or other freight from running out.

I claim:

1. The combination with the side door opening a railway car; of an inside door movable to and from a position for closing said opening, a horizontal support carried by the inner wall of said car above said opening and extending beyond one side wall thereof; a flexible suspension connection between said support and said door, said connection being slidable upon said support, and fastening elements carried by said door and engageable with the side walls of said opening to hold said door in position. 95

2. The combination with the side door opening of a railway car; of a removable inside door movable to and from a position to close said opening, a flexible connection between said door and the side wall of the car above said opening, a plurality of fastening elements carried by said door and engageable with the side wall of said car for maintaining said door in position adjacent the side wall of said car in open and closed 100 position. 105

3. The combination with the side door opening of a railway car; of a removable inside door movable to and from a position to close said opening, a flexible connection between said door and side wall of the car above said opening, a plurality of fastening elements associated with said door and side wall for securing the door in open and closed position thereagainst, and a flexible connection carried by said door said fastening elements being carried thereby in spaced relation to each other. 110 115

4. In combination with an opening, an inside door, a horizontal support above said opening, a flexible connection between said door and said support, a plurality of rotatable fastening elements carried by said door and transversely engageable with the side wall of said opening, to lock said door thereagainst, and weighted lateral projections carried by said fastening elements. 120 125

5. In combination with the side opening of a railway car, an inside door for closing said opening, a horizontal support above 130

said opening and extending beyond one side wall thereof, a slidably mounted flexible connection between said door and said support, tapped bushings transversely embedded in the side walls of said car adjacent said opening, said door having apertures in alignment with said bushings, threaded fas-

teners rotatably carried by said door adjacent said apertures and extendible therethrough for engagement in said bushings, ¹⁰ and weighted lateral projecting handles extending from said fasteners.

ROBERT PEEL BEALE WILSON.
